UNITED STATES PATENT OFFICE.

ANDREW J. O'DAY, OF LELAND, MICHIGAN.

IMPROVEMENT IN ORE-CRUSHERS.

Specification forming part of Letters Patent No. **148,741**, dated March 17, 1874; application filed February 2, 1874.

To all whom it may concern:

Be it known that I, ANDREW J. O'DAY, of Leland, in the county of Leelanaw and State of Michigan, have invented an Improvement in Ore-Crushing and Rock-Breaking Machines, of which the following is a specification:

The nature of this invention relates to an improvement in that class of rock and ore crushing machines wherein an inclined die-plate pivoted at its upper corners to the main frame is vibrated by a system of compound levers acting upon its lower end, to crush the material placed between the vibrating and a stationary vertical jaw. The object of the invention is to so construct the machine as to combine great power and crushing capacity with the least weight and cost, and to double and quadruple the durability of the head and jaw dies, respectively.

Figure 1 is a perspective view of the machine. Fig. 2 is a central longitudinal vertical section at *x x*. Fig. 3 is a horizontal section of the head and head-die at *y y*. Fig. 4 is a cross-section of the jaw-die.

In the drawing, A represents the main frame, cast in the form of an oblong square, open at one end, across which is journaled, in bearings *a*, the driving-shaft B, having a crank, *b*, forged in its middle, to which is strapped a connecting-rod, C, whose lower end is pivoted in the forked rear end of a lever, D, which is pivoted by its trunnions *c* in the plumber-blocks A' under the main frame. Above and behind the trunnions *c* a wrist-pin, *d*, is transversely fixed in said lever, each end of which pin receives a link-bar, E, whose other end is pivoted between lugs *f* cast at the posterior corner of a vibrating jaw, F, by a pin, *e*, passing through the two links and the three lugs. The upper end of said jaw is pivoted to the upper part of the frame by a transverse shaft, *g*, so that in the rotation of the driving-shaft B, the lower end of said jaw will be alternately forced toward and retracted from the head, to crush any material placed between it and said head to a fineness equal to the full opening at the lower end, or less.

In practice it has been found necessary to face the jaw and head of frame with chilled-iron dies or plates, to protect them against the abrasion of the material acted upon.

The hardest chilled head-dies, where the machine is used for crushing black and specular iron ores, will last, on an average, five or six days, and the jaw-dies, three or four days, and frequently not one day's running, when it must be replaced at a heavy expense.

Aside from the advantages in the construction of this machine as a crusher, a still greater advantage is obtained from the peculiar construction of the die-plates, which forms the second part of my invention.

As is well known to users of this class of rock-breakers, the greatest wear is upon the lower faces of the plates. These I make in such a manner that they can be inverted to bring the unworn top ends to the bottom, and to double this advantage I make them double-faced, so that when the vertical corrugations or projecting ribs are wholly worn away on one face a fresh face can be presented to the work by simply reversing the dies.

G is the die-plate at the head or end of the machine, having vertical ribs or sharp corrugations *h* on both faces, loosely placed at the head of the frame, and supported by a stirrup below. This plate may be adjusted toward the jaw by liners placed between its back and the end girt of the frame. To hold it in place a strap, *i*, passing around the head of the frame, with pins *j* passing through slots in the frame into the sides of the die, may be employed, or any equivalent device which will accomplish the purpose. H is the jaw-die, similarly constructed, with the addition of a groove running across the upper and lower ends. The groove at the lower end rests upon a flange turned up from a strap, *k*, bolted to the lower edge of the jaw, while the upper end is confined by a plate, *l*, slipping into the upper groove and bolted to the face of said jaw, as seen in Fig. 2. The jaw may be cast with a flanged lip running across the lower edge to support the lower end of the die; but, as it would be liable to break in use, I prefer to employ the flanged strap *k*, which answers the same purpose and is not liable to break, but if broken is easily replaced.

The original crusher patented by E. W. Blake, June 15, 1858, had the jaw provided with a corrugated face, and a single-faced head-die, and when the face of the latter was worn

it had to be replaced with another die, while the entire jaw had to be renewed when worn. Latterly, an attempt was made to provide the jaw with a movable die-plate by bolts passing through the die and jaw. As soon as the bolt-heads were worn away, the bolts would drop out, and pieces of ore or rock wedging into the bolt-holes would crack the plates. These plates were not reversible, and both they and the head-dies were single-faced.

While I disclaim, broadly, the invention of movable head and jaw dies,

What I do claim as new, and desire to secure by Letters Patent, is—

1. The reversible double-faced die-plate H, having grooves upon its ends, and adapted to be used with ends and sides interchangeably, in combination with removable stops k l, substantially as described and shown.

2. The reversible double-faced die-plate G, adapted to be used with ends and sides interchangeably, in combination with a supporting stirrup and strap, i, substantially as described and shown.

3. In combination with the jaw F, pivoted at its top, and having the lugs f and the link-bar E pivoted between them, the lever D, pivoted to said link-bar, and to the plumber-block A', for the purpose of giving to the lower end of said jaw a rapid initial movement, gradually diminishing in speed and increasing in force, substantially as shown.

ANDREW J. O'DAY.
